UNITED STATES PATENT OFFICE.

EMILE VUILLAUME, OF PARIS, FRANCE.

DOUBLE TOP.

No. 926,083.

Specification of Letters Patent.

Patented June 22, 1909.

Application filed November 25, 1907. Serial No. 403,754.

To all whom it may concern:

Be it known that I, EMILE VUILLAUME, merchant, a citizen of the Kingdom of Belgium, residing in Paris, Seine, France, have 5 invented certain new and useful Improvements Relating to Double Tops, of which invention the following is a full, clear, and exact description.

The present invention relates to improvements in the construction of the double tops which are employed in the game known as "Devil", which as is known are constituted by three parts sometimes formed of one piece but more generally separate and united by a 15 rigid connection that is to say the two outer parts or cones and the median part or pulley which alone is intended to come into contact with the cord for spinning the top.

This invention relates more particularly 20 to imparting greater flexibility and elasticity to the top at the point of junction of the cones, by means of an elastic connection such as a spring for example receiving and deadening all the shocks experienced by the 25 top.

The inventor has found that double tops provided with a rigid connection or even insufficiently elastic at the point of assemblage or junction of the cones have presented the 30 defect of breaking very speedily at the point of assembly which, owing to its reduced diameter, is naturally the weakest part of the top.

In Figure 1 there is shown a top comprising 35 a hollow metal pulley A and two hollow or solid cones of wood, cork, felt etc. B, these latter being retained by an elastic strip or rod C. To insure the proper seating of the cones B against the hollow pulley A, a 40 coil spring D surrounding the strip C is interposed between the cones, bearing at its widened ends against the inner faces b of the latter and thus tending to assist in positioning the cones B upon pulley A after a 45 displacement. The strip C is held in place by any suitable means, for example by the two nuts e.

In the top shown in Fig. 2 the strip C is interrupted and replaced at this point by a 50 spring C'.

In the top shown in Fig. 3 the entire strip is replaced by a metal spring C while in that shown in Fig. 4 it is the spring C which is interrupted at the middle and replaced at 55 this point by a resilient strip or rod C'; in both cases (Figs. 3 and 4) the springs C

are held in place by pins or wedges c'. In Fig. 3⁶⁰ the manner in which the top is deformed when it has been missed by the player and falls to the ground is shown.

Fig. 5 represents a modification of the construction shown in Fig. 1 in which the longitudinal spring D has been replaced either by spiral springs D' lodged in the base of the cones B (see the left hand part 65 of Fig. 5) or by resilient strips D² (right hand part of Fig. 5).

In the top shown in Figs. 6, 7 and 8, the elastic connection is established by one (Figs. 6 and 7) or by several (Fig. 8) springs or 70 india rubber cords. In Fig. 6 the india rubber spring E is pinched and held at its extremities by a rigid wire e the extremities e' of which rest upon the cones B; in Fig. 7 the cord E is retained at its two extremities 75 by a clip E' provided with a perforated stud e² through which there passes a pin e³, the whole protected by a cap E² perforated for the passage of the pin e³. In the top shown in Fig. 8 there are several india rubber cords 80 F retained by hooks f engaged with a pin e³ traversing the cap E²; these cords F can be conveniently combined with textile threads.

In Fig. 9 the pulley or inner part A is 85 constituted by a bi-conical spring, the last convolutions a of which engage in an appropriate groove a' in the cones B. In order to render this pulley A smooth the interstices between the convolutions may be filled with a small quantity of solder a² 90 or preferably a wire A' of half-round section may be employed (Fig. 10).

All these tops present an elastic connection between the cones or external parts B, considered as separate elements. While 95 not departing from the essence of this invention it is possible while still of course preserving the elasticity of the inner part to give a certain elasticity to the cones themselves. This is what is represented in Figs. 100 11, 12 and 13.

In the constructional forms illustrated in Figs. 11 and 12 the cones B with close convolutions (Fig. 11) or loose convolutions (Fig. 12) are formed in one piece with the 105 pulley A or not as desired.

The tops may also be constructed as shown in Fig. 13 in which the cones B are formed by the prolongation of the inner spring C protected by a pulley A as in the case of 110 Figs. 1 to 8.

The modified constructions shown in Figs.

11 to 13 present the advantage of rendering the cones B themselves elastic; all danger of the pulley A breaking as a result of shocks, at the point at which its diameter is smallest, is thus entirely obviated. It will of course be understood that in the case illustrated in Figs. 11, 12 and 13 the cones B may be covered with a suitable envelop of any appropriate material such as metal, 10 leather, india rubber etc.

Finally the cones B may be provided with a cap G (see the section Fig. 14) formed of elastic strips g formed in one piece by slotting or assembled in any convenient manner. 15 Fig. 15 is an end view of this novel top and as shown certain of these elastic strips g present apertures g' through which the screws g^2 for fixing the caps G to the cones B may be introduced.

20 What I claim and desire to secure by Letters Patent of the United States is:—

1. A double top having a hollow double-cone section interposed between and flexibly united to the cones of said top, substantially 25 as described.

2. A double top having cone portions and a hollow double cone section between the same together with flexible means for uniting said parts whereby they may be deranged by shock without injury to the top, substantially as described. 30

3. A double top having cone portions and a hollow double cone section between the same together with spring means for uniting said parts whereby they may be deranged 35 by shock without injury to the top, substantially as described.

4. A double top having independent cone portions and a hollow double cone section interposed between the same together with 40 spring means for uniting said parts whereby they may be deranged by shock without injury to the top, substantially as described.

In testimony whereof I have signed my name to this specification, in the presence of 45 two subscribing witnesses.

EMILE VUILLAUME.
